UNITED STATES PATENT OFFICE.

ALBERT C. CALKINS, OF LOS ANGELES, CALIFORNIA, ASSIGNOR TO THE CALKINS COMPANY, OF LOS ANGELES, CALIFORNIA, A CORPORATION OF CALIFORNIA.

PROSPECTOR ORE-BREAKER.

SPECIFICATION forming part of Letters Patent No. 761,579, dated May 31, 1904.

Application filed July 14, 1902. Renewed October 21, 1903. Serial No. 177,942. (No model.)

To all whom it may concern:

Be it known that I, ALBERT C. CALKINS, of Los Angeles, in the county of Los Angeles and State of California, have invented a new and useful Improvement in Prospector Ore-Breakers, of which the following is a specification.

My invention is designed to provide a light and cheap construction of ore breaker and pulverizer suitable for the prospector's use; and to that end it consists in the peculiar construction and arrangement of the parts of the same with reference to securing this object and to permit of easy cleaning, as will be hereinafter fully described with reference to the drawings, in which—

Figure 1 is a vertical longitudinal section. Fig. 2 is a side elevation. Fig. 3 is a perspective view, on a smaller scale, with one of the jaws turned down for cleaning the interior; and Fig. 4 is a plan view, partly in section, of the parts shown in the position of Figs. 1 and 2.

In the drawings, A and A' represent the two jaws of the ore-breaker, and B is the main frame, mounted upon legs B' and B² and having above the leg B² an upright or standard B³. The jaws A A' are provided at their lower ends with perforated lugs which are offset outwardly from the face of the jaws hinged 25 upon horizontal shafts a and a'. These shafts are arranged at different levels. The jaw A has its axial shaft a on a higher level and held within a housing h of the frame B between two adjusting-screws a' and a², by which the 30 jaw A may be set closer to or farther from the jaw A'. The other jaw A' has its axial center in the frame B at a lower point near the legs B'.

C is the handle-lever for working the jaws. 40 This lever is hinged at its lower end at c' to a short link C', whose other end is jointed at b to the stationary upright B³ of the main frame. Just above the center c' the lever C is jointed at c to perforated lugs at the upper 45 end of jaw A. The lever is also formed with a rigid horizontal extension at this point projecting at right angles to the lever outwardly from the center c and connected by shaft c²

with the two ends of a bail D, the ends of the bail being enlarged at d, as seen in Fig. 2. 50 The bail D passes around and embraces the other jaw A'. The U-shaped bend of the bail is seated in half-round bearings in the side flanges of jaw A' near the top and is detachably held in these bearings, so that it may be 55 lifted out of these bearings to allow the jaw A' to be turned down about its center a', as shown in Fig. 3, whenever it is desired to clean or inspect the interior of the breaker. The means for holding the bail in detachable 60 relation to the jaw A' consists of a clip E, secured by a bolt or lag-screw e to the outer face of the jaw A' and having its upper end hook-shaped, so as to partially embrace the bail. E' is a horizontal cross-bar extending 65 between the outer flanges of the jaw A' and rigidly attached to the same and having a set-screw e' tapped through said bar and bearing against the clip E. When this set-screw is turned up tight, it forces the clip E against 70 the bail and secures the latter in its seats in the flanges of jaw A'. When, however, the set-screw is turned back, so as to allow the clip E to fall away from the bail, the latter may be lifted out of its seats in the jaw to 75 allow the latter to be turned down as described.

The ore-breaker as thus described operates with a compound motion in causing the jaws when the lever C is oscillated to alternately approach and recede from each other 80 and also an up-and-down rubbing motion of one jaw upon the other that produces with a light construction a very powerful crushing effect. By connecting the bail to the right-angled extension of the lever an increased 85 motion is obtained for the front jaw A', and at the same time the powerful effect of a toggle is made available whenever the bail and the centers c and c² fall into line.

On the lever C, opposite its center c and adjacent to the jaw A, there is formed a lug c³, which is adapted to take against a lip l at the top of the jaw A and acts as a stop to prevent the lever from falling too far outwardly when released.

Having thus described my invention, what

I claim as new, and desire to secure by Letters Patent, is—

1. An ore-breaker comprising a rigid framework, two jaws formed at their lower ends with perforated lugs offset outwardly from the face of the jaws, and two axes for the jaws passing through the outer ends of the lugs and arranged at different elevations, and means for causing the jaws to approach and recede from each other at the top and to turn about these axes substantially as described.
2. An ore-breaker, comprising two jaws pivoted at their lower ends, a framework having an upright on one side, a link hinged to the top of said upright and extending inwardly toward the jaws, a vertical lever having its fulcrum in the upper portion of one of the jaws and extending below said fulcrum and jointed to the inner end of the link, said lever having also a right-angular projection on a line with its fulcrum and extending outwardly, and a bail jointed to the outward projection from the lever and passing around and embracing the jaws substantially as and for the purpose described.
3. An ore-breaker comprising two jaws pivoted at the lower ends, a framework having

an upright on one side, a link hinged to the same, a vertical lever having its lower end jointed to said link and jointed at a point above 30 said link to the top of one of the jaws and having also an outwardly-projecting extension, a bail jointed to this outward extension of the lever, and passing around and embracing the other jaw, a retaining-clip for said 35 bail and a cross-bar with a set-screw bearing against this retaining-clip substantially as and for the purpose described.

4. An ore-breaker comprising two jaws pivoted at their lower ends, one of them having 40 at the top a bail-seat and the other one a lip and perforated lugs, a framework having an upright on one side, a link hinged to the same, a vertical lever having its lower end jointed to said link and jointed also to the perforated 45 lugs of the jaw, said lever having on one side an outward extension jointed to the bail and on the other side a stop-lug adapted to engage the lip on the jaw substantially as and for the purpose described.

ALBERT C. CALKINS.
